UNITED STATES PATENT OFFICE.

WILLIAM H. PIKE, JR., OF ORANGE, NEW JERSEY, ASSIGNOR TO NEW YORK ADDING TYPEWRITER COMPANY, OF ORANGE, NEW JERSEY, A CORPORATION OF MISSOURI.

COMBINED TYPE-WRITING AND ADDING MACHINE.

1,037,521.

Specification of Letters Patent. Patented Sept. 3, 1912.

Application filed December 8, 1904. Serial No. 235,980.

To all whom it may concern:

Be it known that I, WILLIAM H. PIKE, Jr., a citizen of the United States, residing at Orange, in the county of Essex and State 5 of New Jersey, have invented certain new and useful Improvements in Combined Type-Writing and Adding Machines, of which the following is a specification.

Combined typewriting and adding machines are necessarily so constructed that while a minimum of amount of power is required to operate the typewriter keys and connections alone, the power to operate these parts in connection with those actuating the adding mechanism is necessarily much greater, and efforts from time to time have been made to reduce the power required for operating the combined machines to about that required to operate the typewriting mechanism, or in other words, each mechanism has been provided with numeral keys from which the adding and recording mechanisms have been actuated and the effort has been to so construct such machines 25 that the numeral keys of the adding machine will not require the exertion of any greater power to operate them than do those of the typewriter.

This is the purpose of my invention hereinafter set forth and to this end I make use 30 in connection with independent typewriter keys of a motor, and driving shaft or other continuously moving actuating means operated therefrom, normally out of operative connection with the working parts of the machine but capable of being operatively connected therewith to operate both the recording and adding means by the power of the motor upon moving any one of a series 40 of numbered parts which I term "starters" as they do not actuate the said mechanisms but merely set parts in position to coact operatively with the motor together with devices which may be used also in 45 connection with other recording machines. as fully set forth hereinafter.

In the accompanying drawings, Figure 1 is a side elevation of sufficient of a combined typewriting and adding machine to 50 illustrate my invention; Fig. 2 is a partial plan view of some of the parts; Fig. 3 a detached view showing the arrangement of spring for lifting a starter; Fig. 4 is a plan view of the machine, only a portion of the 55 parts connected therewith being shown.

For the purpose of illustrating my invention, I have shown parts of a combined typewriter and adder which are not my invention, and which may be of any suitable construction, and some features of my invention may be employed with typewriting machines alone or adding machines alone wherever it is desired to utilize a continuously operating motor power for operating the parts of the machine except the starters 60 or the first movements thereof.

The typewriting features comprise the usual lettered keys Z and the numeral or numbered keys A connected with sliding frames from which connecting rods 100 extend to type levers 101 so that on pressing a key A the corresponding type lever will be thrown toward the platen P, a spring 100^a restoring the parts to position.

The adding devices are operated from 75 a series of numbered starters B, each having a rack 102 engaging a pinion 103 with which turns a cam 104 that operates to vibrate a lever 105, the latter on its first movement being shifted longitudinally and 80 thrown into gear with a pinion 106 connected with the accumulating wheel.

While various other appliances are used in connection with those described, in the actual operation of a combined typewriter and adding machine, it will not be necessary to set them forth or describe their operations in detail, as they may be of any desired character, and as my invention is limited to the means whereby the desired movements are imparted from a continuously moving motor to the parts described, that is to both the recording and adding mechanisms.

The motor M is of any suitable character 95 and operates the working shaft 25 of the machine through the medium of a friction device 108 or clutch of any character that will insure the shaft 25 turning with the motor shaft 109 when the shaft 25 is released, but which will permit the motor shaft to turn independently of the shaft 25 when the latter is prevented from turning.

The shaft 25 is held at rest by a suitable 105 detent, for instance, a pawl or detent 88 pivoted to any fixed support and having a stud 87 which engages the shoulder 29 of a disk 34 on the shaft 25 and holds the said shaft and parts connected therewith in normal or inactive position, a spring 92 con-

neeted with the pawl 88 carrying it toward the disk. When the pawl 87 is moved from the disk, the shaft 25 will remain in clutched relation to the shaft 109 and can turn in the 5 direction of the arrow, and perform the required operations of the mechanism; and after a complete revolution, the shaft 25 and disk are brought to rest by the contact of the shoulder 29 with the stud 87, thus over- 10 coming the actuating connection between the two shafts.

The detent 88 is swung out of position to start operations on the depressing of any one of the starters B in the combined typewriter and adder or of any one of the controlling devices in any other form of apparatus in which the invention may be embodied. In the construction shown, the depression of each starter B brings an inclined 15 face 67 at the edge of the starter bar or stem against the end of an arm 65 secured to a rock shaft 63. Said shaft carries an arm 76; and a pawl 78 pivoted to the lower end of this arm has its forward end held 20 downward in contact with a stud 83 on the detent 88 by the action of a spring 80. The pawl 78 has a shoulder that engages the stud of the detent 88 and when the rock shaft 63 is moved so that the arm 76 is 25 drawn backward the detent 88 is carried away from the shoulder 29 of the disk 34 to permit the movement of the latter.

The rotation of the shaft 25 is the means of operating the adding and recording devices by carrying the starter B farther downward after the detent 88 is shifted out of position. This may be effected by different means, but as shown, a link 91 connects a wrist-pin on the disk 34 with a 30 frame having arms 90 supported on a rock shaft 36, which arms each carry a stud 41 at the rearward end, and beneath this stud the hook of a pawl 59 pivoted to the stem of each key B is brought as soon as the starter 35 is carried downward to a slight extent. To effect this last named result, the pawl 59 has a tail 45 which extends beneath an arm 42 projecting from a fixed shaft 43, and a spring 58 connected at the ends to the pawl 40 and to the stem of the key B tends to maintain the tail 45 against the arm 42. Consequently as the starter B descends, the hooked end of the pawl will swing forward to a 45 position beneath the stud 41 and when the disk 34 is released the arms 90 swing downward by the rotation of the disk, the engagement of the stud with the hook of the pawl will carry the starter downward its full stroke and effect the operations of the computing mechanism. As the arms 90 rise, the 50 contact of the tail 45 of the pawl 59 with the arm 42 will swing the pawl to the position shown in the drawing and out of contact with the arm 90. Prior to this, however, the rising of the starter B carries the 55

inclined face 67 away from the arm 65, so that the shaft 63 can rock under the action of a spring 159 in a direction to carry the arm 76 forward to its first position.

In a combined computing and typewriting machine, the typewriting numeral keys must be carried down at the same time that the adder mechanism is operated, and means are therefore provided for also putting each numbered writing key into connection with the motor, as by means of the power actuated arms 90, while allowing the numeral writing keys to be operated independently. The means for effecting this, as shown, is a hooked pawl 70 pivoted to the frame of each numbered typewriter key A and slotted to receive a stud 47 on the pawl 59 of the co-acting adder key, so that when the pawl 59 is swung forward, the pawl 70 will also be swung forward and its hooked end will be 85 brought below the stud 41 which will engage the same and carry down the type key A.

The starters B are restored to position by means of springs 96 connected to studs on the keys and to studs on standards in the frame of the machine. As the disk 34 rotates after being released, a stud 86 thereon is brought beneath and elevates the pawl 78, so that it escapes from the stud 83 of the detent 88 which can then swing to a position 95 for its stud 87 to make contact with the shoulder 29 when the latter arrives in position to meet it.

While I have referred to a continuously rotating driving shaft 25, and to a rocking working shaft, it will of course be understood that the said driving shaft may be operated by a reciprocating slide or other equivalent working element connected with the mechanisms of the machine.

It will be seen from the above that while the numeral typewriter keys may be operated without any more exertion than in ordinary typewriting, and independently of the adding mechanism, the starters can be 100 operated with as little or even less exercise of power by the operator, as they do not actuate the adding devices but after the partial depression of any one of the starters the further operations are performed by the 110 continuously moving motor until they are 115 completed, when the working parts will be brought to and automatically arrested in normal positions.

I do not here claim broadly the combination in an adding machine, of a working shaft and driving shaft and connections as here shown and also set forth in my application Serial No. 209,673.

Without limiting myself to the precise 120 construction and arrangement of parts shown, I claim,

1. The combination with recording mechanism, numbered and lettered hand-actuated keys for operating the recording mechanism,

and an adding mechanism, of a driving shaft, means for continuously rotating said shaft, connections whereby said shaft may actuate both the recording and adding mechanisms, means normally preventing actuation of said connecting means, and a series of numbered starters each adapted to control the actuation of said connecting means by the driving shaft.

10 2. In a combined typewriting and adding machine, the combination with adding mechanism, suitable recording mechanism, hand actuated lettered and numbered keys for operating said recording mechanism, a working shaft adapted to operate both the adding and recording mechanisms, a continuously rotating driving shaft, a frictional driving connection between the shafts, means for automatically arresting the working shaft after each recording and adding operation, and means for releasing said shaft at will.

3. In a typewriting and adding machine, a series of numbered shifters, recording devices, and a working shaft from which said devices are operated, combined with a continuously operating driving shaft adapted to actuate the working shaft, means normally checking rotation of the working shaft, means controlled by depressing any one of the shifters prior to each operation in adding for releasing the working shaft, and automatic means for arresting the working shaft after each operation.

35 4. In a typewriting and adding machine, a series of numbered adjustable devices, recording means and a working shaft from which said devices and means are operated combined with a continuously operating driving shaft, and means for arresting the working shaft after each recording operation, said arresting means operable to release the working shaft on the adjustment of any one of said numbered devices.

45 5. In a combined typewriting and adding machine having typewriting and adding mechanisms, a working shaft from which said mechanisms are operated, a continuously rotating driving shaft, means adapted to arrest rotation of the working shaft, means operable at will for enabling the driving shaft to actuate the working shaft, and automatic means for rendering operative the means for arresting the working shaft after the completion of each operation, in adding or recording, substantially as set forth.

60 6. In a combined typewriting and adding machine having typewriting and adding mechanisms, a working shaft from which said mechanisms are operated, a continuously rotating driving shaft in frictional engagement with the working shaft, means for holding the working shaft from rotating, means for releasing the working shaft

prior to each operation, and automatic means for causing said holding means to arrest rotation of the working shaft after each operation, substantially as set forth.

7. The combination with the typewriting and adding mechanisms including a series of numbered keys for each mechanism, of a working shaft, a bar 41, means for connecting said bar with any adder key and the corresponding typewriting key on depressing the adder key, arms carrying said bar, a crank pin carried by the working shaft, and a link connecting the crank pin and said arms, substantially as set forth.

75 8. The combination with the typewriting and adding mechanisms including a series of numbered keys for the typewriter devices and numbered starters for the adder mechanism, of a working shaft, a bar 41, means for connecting said bar with any starter and a corresponding typewriter key on depressing the starter, arms carrying said bar, a crank pin carried by the working shaft, a link connecting the crank pin and said arms, a detent for holding the working shaft out 90 of operation, and means for shifting the detent from the said depressed starter, substantially as set forth.

95 9. In a typewriting and adding machine, the combination with typewriting mechanism and adding mechanism, of a continuously rotating shaft, means for operating the typewriting mechanism therefrom, a series of starters each adapted to be adjusted to effect an operation of the adding 100 mechanism, and means for moving either starter a predetermined distance by power conveyed from the continuously rotating shaft.

10. In a typewriting and adding machine, the combination of a series of hand operated numbered keys, recording devices adapted to be operated by said keys, an adding mechanism, a continuously rotating shaft, a working shaft, a frictional connection between said shafts, means for normally holding said working shaft stationary, and a series of starters each adapted to release said working shaft and cause the connection of the adding mechanism and one of the 110 numbered keys with said shaft.

11. The combination in a machine of the character described, of independent recording and adding mechanisms, a continuously running motor, a working shaft, a stop normally preventing rotation of the working shaft, a series of manually controllable devices, each corresponding to one of the keys of the recording mechanism and adapted to render said stop inoperative and control 120 connection of the working shaft with both the adding and recording mechanisms, and means for automatically restoring said stop to position to arrest rotation of the working shaft.

12. The combination in a machine of the character described, of independent recording and adding mechanisms, a continuously running motor, a working shaft, a shifttable
5 stop normally preventing rotation of the working shaft, a series of manually controllable devices, each corresponding to one of the keys of the recording mechanism and adapted to move said stop to release the
10 working shaft and to control connection of said shaft with both the adding and recording mechanisms, and means actuated by said shaft for automatically restoring said stop to operative position before the working
15 shaft has completed a rotation.
13. In a machine of the character described, the combination of accounting and recording mechanisms, actuating means therefor, a continuously running motor, and
20 a series of manually adjustable numbered devices, the operability of the actuating means by the motor being controlled by each of said devices.
14. The combination in a machine of the
25 character described of recording mechanism, adding mechanism, a series of numbered

shifting devices, actuating means for said mechanisms, a continuously operating driving shaft, means for connecting said actuating means with the driving shaft, and means for arresting automatically the movement of the actuating means after each adding and recording operation, said arresting means controllable from each of the said shifting devices. 30

15. The combination with recording mechanism, numbered and lettered hand actuated keys for operating the same, and an adding mechanism, of a series of numbered starters, a driving shaft, means for continuously rotating the shaft, and means controllable from each of said starters, for effecting connection of the shaft with both the recording and adding mechanisms. 35

In testimony whereof I have signed my name to this specification in the presence of two subscribing witnesses. 40
